UNITED STATES PATENT OFFICE.

JAMES H. MARKHAM AND ARTHUR M. CRUGAR, OF OAKLAND, CALIFORNIA.

TOY BASEBALL GAME.

Application filed June 15, 1925. Serial No. 37,030.

Our invention is a toy baseball game in which a representation of a baseball diamond and field is set up on a table and a ball is rolled from the pitcher's box towards the plate and the batter releases a spring actuated bat to strike the ball. The game is one of skill in both the pitching and striking of the ball, that is, unless the person playing the part of the pitcher rolls the ball to count strikes without the ball being hit, the skill of the person batting will probably win runs for the batter's team. The game has certain hazards representing field and instop catches which would put the batter out.

Our invention is preferably mounted on a sectional table having four parts joined together at the center lines to represent a baseball field in which one of the corners or sections represents a baseball diamond. The legs of the table are preferably folded so that the sections may be stacked together for storage or transporting. The plate is represented by a slight inclined plane with a box at the back to catch the ball and a spring actuated bat is mounted adjacent the incline so that on release of the bat the spring will cause it to strike the ball. The bat may be utilized to hit straight or "strike" balls as well as throws which would not exactly cross the plate but be called "balls."

The baseball field is provided with a fence at the outside edges and with "foul" lines. The fields have apertures provided therein with a low partition at the back and a suspended fabric bag to indicate "field" catches when the ball rolls into such apertures. The "infield" along the line preferably of the runs from first to second, and second to third, base have a plurality of small apertures with partitions at the back thereof to indicate "infield" catches when the ball after being struck rolls into these apertures or receptacles.

The ball is "pitched" by the use of a grooved slat having a recess at its upper end to engage and hold the ball and a handle secured in a mid-position to the slat extending at right angles therefrom so that a player may incline the slat until the ball rolls out of the recess following the groove. The player acting as pitcher may thus aim the ball at the home plate to endeavor to

secure "strikes" or he may intentionally endeavor to roll balls with the object of fooling the batter to strike at these, which the batter would most probably miss.

Other features of our invention will appear from the following description and drawings, in which—

Figure 1 is a top perspective view illustrating the baseball field and the game as a whole.

Figure 2 represents the "home plate" and the "catcher" and is a vertical longitudinal section on the lines 2—2 of Figures 3 and 4, showing the inclined plane for the ball to roll up and the elongated box forming the "plate" and the "catcher".

Figure 3 is an end elevation of Figure 2 in the direction of the arrow 3 showing the back-stop arrangement for the "catcher".

Figure 4 is a plan of part of Figures 2 and 3 as if in the direction of arrow 4 of Figure 2.

Figure 5 is a developed view of one of the partitions forming part of the "in" or "out" field catching receptacles.

Figure 6 is a side elevation of the table with the "fence" and "foul" lines removed to illustrate the construction of the folding and demountable table.

Figure 7 is a bottom view of the table showing the legs folded and the cleats to fasten the sections of the table together.

Figure 8 is a plan view of the sections of the field stacked taken in the direction of the arrow 8 of Figure 9.

Figure 9 is an elevation of the stacked sections of the table in the direction of the arrow 9 in Figure 8.

Figure 10 is a plan of the "pitching" device showing the grooved slat the receptacle in the end thereof and the handle.

Figure 11 is an end view of the "pitching" device taken in the direction of the arrow 11 of Figure 10 showing the slat in side elevation.

Figure 12 is an end view of the slat taken in the direction of the arrow 12 in Figure 10.

Figure 13 is a side view of the detachable handle.

Figure 14 is a section through the batting device illustrating the spring actuation of the "bat" and the trigger release to be oper-

ated by the "batter", as if taken on the line 14—14 of Figure 15 in the direction of the arrow.

Figure 15 is a bottom view of Figure 14 in the direction of the arrow 15.

Figure 16 is an elevation of the "bat" showing the squared end to wind the spring and to cause the actuation of the "bat".

Figure 17 is a plan of the "bat" in the direction of the arrow 17 of Figure 16.

Figure 18 is a side view of the trigger button to be pressed by the "batter" to cause the swinging of the "bat".

Referring particularly to Figure 1 the baseball field is designated generally by the numeral 1 having the diamond 2 marked out in one corner, the right center left field being indicated by the numerals 3, 4, and 5. The "pitcher's" box is indicated by the numeral 6, the "home plate" by the position 7 and the first, second and third bases by the numerals 8, 9, and 10. The fence 11 is formed by a strip of cloth secured at its upper end to a post 12 in the "center field" corner, the diagonal posts 13 secured at the "right" and "left" fields engage the upper edge of the cloth which is stretched to a point 14 positioned some place adjacent the diamond. A series of buttons 15 secure the lower edge of the cloth strip, thereby forming the fence.

The "foul" lines are indicated by the painted lines on the diamond from "home plate" to "first" and "third" bases and by cardboard partitions 16 which are formed with tongues 17 fitting into slots in the surface of the table, thus any balls struck going between the partition 16 and the portion of the fence along the "right" and "left" fields would be counted as a "foul".

The "catches" in the "right", "center" and "left" fields are designated by the numeral 18 and are formed by large openings 19 through the table to which is secured cotton fabric 20 to form a pocket or receptacle. To increase the hazard flexible wall strips 21 are inserted on the far side of the openings 19 to "stop" any balls which might be struck sufficiently hard to pass across the openings without falling into the pockets. These strips may be bent into position and are provided with a small metal socket 22 which forms a groove with two flanges and with recessed corners 23 to engage the material forming the top of the table and thereby hold the small wall sections into position.

The "infield" catches 24 which are preferably situated adjacent the running lines between the "first" and "second", and "second" and "third" bases are constructed in the same manner as the "outfield" catches 18.

The "home plate" and the "strike" catcher 25 is formed from a small elongated box 26 having a base 27 and inclined front edge 28, side walls 29, back wall 30. A "catcher"

partition 31 is attached to the back wall 30 by being formed with a tongue 32 which may be inserted over the inside of the back wall. The inclined surface 28 is carpeted with a roughened strip 33 of flat fabric so that the ball with which the game is played will more readily be guided up the incline. A pair of nails 34 secured to the base 27 are positioned to be inserted in sockets in the table, and thus hold the "home plate" 75 device in its proper position. (Reference is directed particularly to Figures 2, 3 and 4.)

The "pitching" device, as shown in Figure 10 is constructed of a grooved slat 35, having a socket 36 at its upper end, and bevelled at its lower end 37, the groove being indicated by the numeral 38. The slat is enlarged at the back having a lug 39 with a dove-tailed groove 40 extending transversely across the slat. The handle 41 is preferably formed of wood and has a key shaped end 42 to form a tight fit in the dove-tail groove 40 so that the handle and the slat may be secured together. In operating the device a light ball, preferably made of cork is inserted in the socket 36 and the player positions the lower end in the "pitcher's" box 6 and then raises the socket end until the ball rolls out of the socket down the groove. The "pitcher" operating the handle 41 may give "slow" or "fast" balls by raising the slat slowly until the ball will merely topple out of the socket 36, or he may raise the end rapidly so that as the ball rolls out of the socket he increases the inclination of the slat before the ball reaches the table.

The "batting" device as shown particularly in Figures 14 to 18, comprises a bat 43 formed with a curved striking face 44, a vertical stem 45 and a squared end 46. This stem is fitted through an aperture 47 in the top of the table and passes through a fixed plate 48 and through the rotatable sleeve 49. A disc 50 is secured at the lower end of the sleeve 49 which projects below the plate 48 and a dog 51 is secured to the disc, such disc having a squared socket 52 to engage the squared end 46 of the "bat". A coiled spring 53 is secured to the sleeve 49 and in a fixed position 54 to the bottom of the table. A pawl 55 pivotally mounted on the plate 48 by the pintle 56 has a tooth 57 to engage the dog 51. A tension spring 58 normally presses the tooth inwardly. A bell crank trigger 59 is carried by a pivot pin 60 on the bottom of the table and has a trigger end 61 to engage the end 62 of the pawl. A slide stem 63 having a button 64 at its outer end is slideable through an aperture 65 in the table.

The pitching device is wound up by inserting the "bat" into the position described above, and turning it to give an additional twist to the spring 53 which is always ten-

sioned to unwind until the dog 51 and the tooth 57 engage. The "batter" then presses the button 64 when he judges the proper moment to operate the trigger 59 to swing the pawl 55 outwardly and thereby release the dog 51 so that the sleeve 49 and the bat may rotate until the stop pin 66 engages the dog 51 and thereby prevents unwinding the spring 53.

10 The construction of the table to mount the baseball game is preferably demountable when formed in sections. (See particularly Figures 1, 6, 7, 8 and 9.) The "diamond", "right center" and "left field" sections preferably form the four sections of the table, each section having a rim 70 around its periphery. A pin 71 across each outside corner, a leg 72 pivoted thereon, and having resilient braces 73 extending 20 through an aperture 74 in the leg, and having fingers 75 to engage in sockets 76 in the rim of the sections. A cleat 77 having thumb screws 78 secures the four sections together along one diametrical line and the cleat 79 having a recess therein where it passes over the cleat 77 is also secured by thumb screws 80 to the table sections on the other diametrical line. (See Figures 6 and 7.) It will thus be seen that the sections of the table may be taken apart and stacked as shown in Figures 8 and 9. Practically all the elements of construction, including the "pitching" device, and the walls at the "field catching" pockets may be stored 25 in the space at the back of each section of the table. Thus the device may be packed conveniently for shipping or transport or storage.

Our invention may be materially changed 40 in details without departing from the spirit thereof and may not be made sectional and demountable unless desired.

The game may be played by any number 45 up to nine of players on a team, each player being represented by a "man" comprising a numbered or initialed disc or the like. Various rules may be utilized,—"over the fence" giving a home run, a "hit" into the far corner of the "center field" giving a 50 "two-base" hit, and the others giving a "one-base" hit, or such other rules.

Having described our invention, what we 55 claim is:

1. A baseball game comprising in combination a table having a top painted to represent a baseball field, having a diamond in one corner, a plurality of openings in the field portions, pockets in said openings and

walls at the back of the pockets and immediately adjacent thereto positioned to stop 60 balls and deflect them into the pockets in which the walls are formed by flexible strips with means to detachably secure the strips to the edge of the openings.

2. In a baseball game comprising a pitching device having a slat with a recess at one end and a groove along which a ball may roll, a home plate and catching device having an elongated box with an inclined end facing the pitching device and means 70 adapted to strike a ball after rolling up the said incline.

3. In a baseball game, as claimed in claim 2, in which the means to strike the ball comprises a pivotally mounted bat, a spring 75 to actuate the bat, means to tension the spring and a trigger mechanism to release the spring and thereby causing the swinging of the bat.

4. A batting device for a baseball game 80 comprising a bat, a vertical stem connected thereto, a rotary sleeve adapted to engage and hold the said stem, a spring tensioned to rotate the sleeve, a dog attached to the sleeve and a pawl positioned to engage the dog and a trigger mechanism to actuate the pawl to release the spring and thereby swing the bat.

5. A pitching device for a baseball game, 85 comprising a slat having a groove therein and recesses at its upper end adapted to retain a ball, a dove-tailed cross groove in its lower face and a detachable handle secured in such dove-tailed groove.

6. In a baseball game, a home plate and 90 catching device formed of an elongated box having an inclined end face, a back wall extending above and beyond the sides of the box adapted to catch a ball which may pass beside the box and means to retain the 100 box on a table.

7. A baseball game comprising in combination a knock-down sectional table formed in a plurality of separable sections, means to hold such sections together, a series of 105 posts secured to the different sections, a strip of fabric stretched between the posts and the edges of the sections forming a "fence" and representations of a baseball diamond and a pair of partitions forming a "foul 110 line" secured to two sections of the table.

In testimony whereof we affix our signatures.

JAMES H. MARKHAM.
ARTHUR M. CRUGAR.
